RECORDING VISCOSIMETER

Leon M. Evans, Houston, Tex., assignor to The Texas Company, New York, N. Y., a corporation of Delaware

Application July 24, 1951, Serial No. 238,308

4 Claims. (Cl. 73—59)

1

This invention relates to certain improvements in viscosimeters, and more particularly to viscosimeters of the type in which the force reaction to a submerged member, rotatably driven in the liquid undergoing test, is measured to indicate the viscosity of the liquid. A viscosimeter of this general type, and on which this invention is an improvement is shown and described in the copending application of Gerhard Herzog, Serial No. 47,803 filed September 4, 1948, now Patent No. 2,643,543. Figures 2, 4 and 5 of the Herzog application drawings illustrate the particular type of apparatus on which this invention is an improvement.

It is often desirable to make viscosity measurements at various temperatures, generally above room temperature, and consequently a source of heat to be applied to the liquid undergoing test is necessary in most cases. One method of heating is by use of electricity, and generally a heater coil is arranged in or around the container for the liquid under test.

A problem has existed in instruments of this type of providing a satisfactory means for connecting a source of electrical energy to the heater coil, in view of the fact that the container is in substantially constant motion throughout the period of taking measurements. It has been proposed to use a pair of mercury pools as conductors but this is somewhat cumbersome, since it requires additional apparatus and space. The present invention provides a means for connecting the electric heater element surrounding the specimen cup to a source of electrical power directly through the supporting members of the specimen cup assembly.

The accompanying sheet of drawing shows, somewhat in diagrammatic form, a preferred embodiment of this invention. Since this invention is an improvement on the apparatus shown and described in the above identified application, only that part of the complete apparatus necessary to understand the invention is illustrated herein.

The specimen cup 100 is rigidly mounted in a supporting yoke member 11. An electric heater element 12 is mounted on the specimen cup in any suitable manner, so long as it is arranged to transfer heat to the liquid contained in the cup. A frame or base member 13 serves as a support for the entire instrument but only a part of the frame is shown in the drawing. The yoke member 11 is supported within the frame by a pair of torsion wires 14 and 15. These torsion wires are connected at their outer ends to the frame, in order to support the entire specimen cup and

2

yoke assembly in a torsionally resilient manner. The lower torsion wire 15 is insulated from the frame 13 by means of an insulating bushing 16. A second bushing 17 serves to insulate the lower torsion wire 15 from the yoke member 11. Bushings 16 and 17 are rigidly affixed to the frame member 13 and the yoke 11 respectively. The torsion wire 15 is rigidly connected to the threaded plugs 18 and 19 which may be screwed into the bushings 16 and 17 as shown. Since the upper torsion wire 14 is connected electrically to the frame and to the yoke member, the latter members may serve as a return circuit for current applied to the heater coil 12. A short insulated lead 20 is used to connect the lower torsion wire 15 to one side of the electrical heater 12. The other side of the heater coil may be connected to any part of the frame or yoke assembly in some convenient manner. As shown in the drawing, 15 a short lead 21 is connected between the other side of the heater and the yoke member 11.

As shown and described in the above mentioned copending application, a rotor member 22 is mounted for rotation within the specimen cup 10. Suitable driving means (not shown) is provided for the rotor.

The upper torsion wire 14 is mounted in a bearing assembly 23 and a servomotor, shown diagrammatically on the drawing, is connected to 30 drive the upper torsion wire in response to movements of the yoke assembly, all as shown and described in the above-mentioned application.

As will be apparent to those skilled in the art, it may often be desirable to maintain a predetermined temperature of the material within the specimen cup and this may be achieved by thermostat control of the electrical supply.

While a preferred embodiment of the invention has been shown and described herein, various modifications within the scope of the appended claims will be apparent to those skilled in the art.

I claim:

1. In a viscosimeter of the type in which the force reaction to a member rotatably driven in the liquid undergoing test is measured to indicate the liquid viscosity, the combination comprising: a frame forming a support for the viscosimeter; a container for the liquid undergoing test; a rotor member supported for rotation within said container; a mechanical suspension for said container including a yoke member to which said container is rigidly attached, and a pair of torsionally resilient wires attached at one end of each to the top and bottom of said yoke member, the other ends of said wires being attached to

said frame to support the container and yoke assembly in torsionally resilient fashion in said frame; insulating means interposed between at least one of said wires and said frame; an electrical heating element mounted on said container in heat exchange relation thereto; means connecting the yoke ends of said wires to said electrical heater; and means affording connection to the outer ends of said wires to a source of electrical energy.

2. In a viscosimeter of the type in which the force reaction to a member rotatably driven in the liquid undergoing test is measured to indicate the liquid viscosity, the combination comprising: a container for the liquid undergoing test; a rotor member supported for rotation within said container; a torsion suspension for said container including a pair of members disposed on opposite sides of said container, each of said members being electrically conductive and at least one being torsionally resilient; an electrical heating element carried by said suspension and

mounted in heat exchange relation to said container; and means including said members for connecting said heating element to a source of electrical energy.

5. A combination as defined by claim 2 in which the heating element is mounted on said container in heat exchange relation thereto.

6. A combination as defined by claim 2 in which the said members comprise a pair of wire-like elements.
